UNITED STATES PATENT OFFICE

91,847

DESIGN FOR AN ASH TRAY

Arthur C. Sias, Meriden, Conn., assignor to The
Meriden Gravure Company, Meriden, Conn., a
corporation

Application October 11, 1933, Serial No. 49,454

Term of patent 3½ years

To all whom it may concern:

Be it known that I, ARTHUR C. SIAS, a citizen of the United States, residing at Meriden, in the county of New Haven and State of Connecticut, have invented a new, original, and ornamental Design for an Ash Tray, of which the following is a specification, reference being had to the accompanying drawing, forming part thereof.

Fig. 1 is a plan view of an ash tray showing my new design;

Fig. 2 is a side view of the same;

Fig. 3 is a sectional view on the line 3—3 of Fig. 2; and

Fig. 4 is a perspective view of my design on a reduced scale.

My newly designed ash-tray, circular and cup-shaped in general plan, is characterized by a massive ring of conical cross-section having symmetrically-curved outer and inner walls rising to a sharp peak forming a continuous linear circle, and is further characterized by a relatively slender, centrally-arranged, upstanding, rectangular, flat-sided, post rising to a height substantially above the upper edge of the rim and formed with two notches crossing each other at a right angle for the support of a cigar or cigarette.

I claim:

The ornamental design for an ash tray as shown as described.

ARTHUR C. SIAS.
